UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,828, dated October 29, 1895.

Application filed September 27, 1895. Serial No. 563,942. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

- 1. The design consists of the figure of a griffin rampant placed at regular distances over the surface of the paper with a plain vertical band on each side of said figure, as represented in the accompanying drawing.
- 2. The border of the design is also formed of the figure of a griffin rampant inclosed in a

large shield-shaped ornament with ornamental scrolls springing from the base of said ornament and a plain vertical band on each side of said ornament, as shown in the drawing.

What I claim is—

1. The design for wall paper herein shown and described.
2. In the design for wall paper, the border herein shown and described.

Witness my hand this 24th day of September, 1895.

CHARLES BOOZ.
